CIRCUIT INTERRUPTER

Thomas E. Curtis, Hampton, and James M. de Montmollin, Griffin, Ga., assignors to Southern States Equipment Corporation, a corporation of Georgia

Application May 8, 1953, Serial No. 353,742

11 Claims. (Cl. 200—114)

This invention relates to circuit interrupters and more particularly to interrupters of the type commonly referred to as load break cutouts or fuses.

Electric cutouts which incorporate a fusible element disposed within a fuse tube of insulating material are adapted for interrupting overload or fault currents by expulsion action in response to the melting of the fusible element and, if desired, load currents may be interrupted by physically breaking the fusible element thereby to draw an arc within the fuse tube which is extinguished by expulsion action in known manner. The circuit interrupting action may be accompanied by withdrawal of one end of the fusible element from the fuse tube by means of an ejector element constructed of a low mass and provided with biasing means arranged to effect a rapid withdrawal of the fuse link from the fuse tube. Since the fusible element is commonly broken by means which is manually operable and since fusible elements of high current ratings are difficult to break by ordinary manual means, a load break cutout is needed which inherently is capable of breaking fusible elements of high current ratings without requiring the operator to apply heavy forces to the mechanism which tend to cause undesired stresses in and movement of the parts.

A principal object of this invention is to provide a load break cutout which inherently is capable of physically breaking heavy fusible elements of high current ratings.

Another object of this invention is the provision of a load break cutout which is arranged to afford a substantial mechanical advantage so as to enable the operator to break large fusible elements mechanically without the necessity of applying excessive forces to the device.

Still another object of the invention is to provide a load break cutout having a fuse holder which inherently remains substantially stationary in its service position until after the fusible element is ruptured during a load breaking operation.

The invention in one form as applied to a load break cutout comprises a conducting element pivotally supported by a fuse tube, an ejector element pivotally mounted on the conducting element, a fusible element arranged so as normally to maintain the conducting and ejector elements in their normal positions, and crank means for moving the ejector element out of its normal position relative to the conducting element thereby to break the fusible element and allow the ejector element promptly to withdraw one end of the fusible element from the fuse tube.

For a better understanding of the invention reference may be had to the following description taken in conjunction with the accompanying drawings in which Fig. 1 is a side view of a load break cutout embodying the invention, Fig. 2 is an enlarged view of a portion of the structure shown in Fig. 1 as seen from underneath with the parts occupying an intermediate position, and in which Fig. 3 is a detailed, enlarged view of a portion of

2

Fig. 1 as seen from the opposite side of the device from that depicted in Fig. 1 with the parts in an intermediate position.

With reference to Fig. 1 the numeral 1 represents a support arm which at its left-hand end is mounted on a supporting structure (not shown) and which at its right-hand end is secured to insulators 2 and 3. Affixed to the upper end of insulator 2 is a terminal element 4 which is provided with openings 5 and 6 for cooperating with a longitudinally split bolt 7 by which a conductor (not shown) may be secured to the terminal 4. A hood 9 is pivoted at 10 to the terminal 4 for limited rotary movement and is provided with a latching surface 11. A brush contact 12 is also secured to the terminal 4. Latch 11 and contact 12 cooperate with the movable fuse assembly generally designated by the numeral 13 in a manner to be more specifically described hereinafter.

A terminal 14 is affixed to the lower end of insulator 3 and is provided with a slot 15 which, as shown in Fig. 1, receives one portion of the longitudinally split terminal bolt 16 for connecting the terminal 14 with a circuit conductor (not shown). Terminal 14 is also provided with a pair of spaced extensions 14a between which the contact brush 17 is mounted. The spaced extensions 14a of the terminal element 14 are provided with jaws 18 which cooperate with portions of the fuse assembly 13 in a manner to be described hereinafter.

The fuse assembly 13 comprises a contact element 19 which is provided with a contacting surface 20 for cooperating with the contact brush 12 and is also provided with an upwardly extending latching portion 21 which as indicated in Fig. 1 is engageable with the latching surface 11 of the hood 9. Secured to the upper end of the contact 19 is a cap member 22. If desired, cap member 22 and contact member 19 may be constructed in accordance with the disclosure of our application Serial No. 338,836, filed February 25, 1953, and assigned to the assignee of this invention. It will be understood that insofar as the principles of this invention are concerned any known assembly arrangement could be used instead of the above-referred-to structure comprising contact member 19 and cap member 22.

As is well known in the art, a fusible element is disposed within the fuse tube 23 and is secured to the contact 19 at its upper end and provided with a projecting portion 24 which extends out of the lower end of the fuse tube 23.

Affixed to the fuse tube 23 by means of the screw 25 is a terminal element 26 which is provided with an opening 27 therein for receiving a switch stick or other operating member. Terminal element 26 is also provided with a pivotal mounting 28 for the conducting element 29 which is provided with a contacting surface 30 for cooperating with the brush contact 17. The conducting element 29 is also provided with a projection 31 which engages a portion 32 of the terminal element 26 when the conducting element 29 is in its normal position. Conducting element 29 is maintained at its normal position by the conductor 24 which is secured to the conducting element 29 by the connector 33 which is screwed into the threaded opening 34 in the conducting element 29 so as to grip the end of conductor 24 against the ridged surface 35 of element 29.

The assembly 13 is pivotally mounted in the jaws 18 by means of a pin 36 which interrelates the conducting element 29 with the trunnions 37 and 38 which in turn are rotatably supported by the jaws 18. Trunnions 37 and 38 are interconnected by an integrally formed offset portion 39 as is best shown in Fig. 2.

As is best shown in Fig. 2 an ejector element 40 is pivotally supported by the pin 36 which is disposed in openings formed in the projecting portions 40a and 40b

of the ejector. A coiled spring 41 is also disposed about the pin 36 and between the projections 40a and 40b and is arranged with its ends respectively in engagement with the offset portion 39 and the ejector 40 so as to bias ejector 40 for clockwise rotation as viewed in Fig. 1 against the holding action of the conductor 24. Counterclockwise rotation of offset portion 39 and of trunnions 37 and 38 is limited due to engagement of offset portion 39 with a surface 29a of conducting element 29 when the parts occupy the positions indicated in Fig. 1. The circuit through the cutout comprises terminal 14, brush contact 17, conducting element 29, the fusible element having the outwardly extending portion 24, contact 19, brush contact 12, and the terminal 4.

Upon the occurrence of a fault or overload condition on the circuit controlled by the device, the fusible element disposed within the fuse tube 23 melts the ejector 40 under the action of spring 41 promptly withdraws the conductor 24 and parts associated therewith from the lower end of the fuse tube 23. The arc drawn within the fuse tube 23 is extinguished by expulsion action in known manner. During or immediately after this period the pivot 28 moves clockwise about pin 36 as a center from the position indicated in Fig. 1 due to the weight of the structure 13 and to the biasing action of the brush contact 17. Continued rotation of pivot 28 about the pin 36 as a center eventually causes downward motion of the upwardly projecting portion 21 of the contact 19 thereby to disengage latching surface 11. Thereafter the whole structure 13 swings in a clockwise direction about the trunnions 37 and 38 and pin 36. In this way an isolating gap is established between the terminals 4 and 14.

The arrangement above described is also adaptable according to this invention for use as a device for interrupting normal load current; i. e. current which is insufficient in magnitude to melt the fusible element. In this connection it will be observed that the trunnions 37 and 38 and offset portion 39 are integrally formed with a manually operable handle 42 which at its right-hand extremity is provided with an opening 43 for receiving the laterally projecting portion 44 of a switch stick 45. Thus with the parts occupying the positions shown in Fig. 1 a downward pull on the switch stick 45 causes the trunnions 37 and 38 and the offset portion 39 to move in a clockwise direction about the pin 36. Since the offset portion 39 is in engagement with the ejector 40, the ejector 40 is forced to rotate in a clockwise direction about the pin 36 as viewed in Fig. 1. Thus a tension force is applied to the conductor 24 which is sufficient to break the fusible element disposed within the fuse tube 23. Upon rupture of this element an arc is drawn and subsequently extinguished by expulsion action in known manner. The breaking of the fusible element takes place without causing any appreciable movement of conducting element 29 or of tube 23 according to a feature of the invention. For this reason the latching surface 11 snugly and securely holds the projecting portion 21 of the contact 19 in a contact-making position until ample opportunity has been afforded to rupture the fusible element within tube 23 and to extinguish the arc drawn therein. Thus destructive arcs between contact surface 20 and brush contact 12 are prevented. Furthermore the distance between the opening 43 to the pin 36 is several times the distance between the notched portion 40c of the ejector 40 in which conductor 24 is disposed and pin 36. Thus a desirable mechanical advantage is afforded which according to a feature of the invention makes it possible to easily break heavy fusible elements of large current ratings.

It will be observed that whether the conducting element 29 occupies the position shown in Fig. 1 or whether the ejector element 40 and conducting element 29 have been moved to the position indicated in Fig. 3, the biasing action of spring 41 tending to rotate the ejector element 35

5 is in such a direction as to tend to withdraw conductor 24 from the lower end of tube 23.

While we have shown and described a particular embodiment of the invention, we do not wish to be limited thereto and intend in the appended claims to cover all such changes and modifications as fall within the true spirit and scope of the invention.

What we claim as new and desire to secure by Letters Patent of the United States is:

1. An electric fuse comprising a fuse tube, a fusible element disposed in said tube and having a portion thereof extending out of one end of said tube, a conducting element movably supported by said tube and having a normal position with respect thereto, an ejector element movably supported by said conducting element and having a normal position with respect thereto, said portion of said fusible element being normally interrelated with said ejector element so as to hold said ejector element in its normal position relative to said conducting element and engageable with said ejector element for moving but movable independently of said conducting element and engageable with said ejector element for moving said ejector element relative to said conducting element thereby to break said fusible element.

2. An electric fuse comprising a fuse tube, a fusible element disposed in said tube and having a portion thereof extending out of one end of said tube, a conducting element movably supported by said tube and having a normal position with respect thereto, an ejector element movably supported by said conducting element and having a normal position with respect thereto, said portion of said fusible element being normally interrelated with said conducting and ejector elements so as to hold said conducting and ejector elements in their normal positions, and manual means operably related with said ejector element and movable independently of said conducting element for engaging and moving said ejector element out of its normal position relative to said conducting element thereby physically to break said fusible element.

3. An electric fuse comprising a fuse tube, a fusible element in said tube and having a portion thereof extending out of one end of said tube, a conducting element movably supported by said tube and having a normal position with respect thereto, an ejector element pivotally mounted on said conducting element and having a normal position with respect thereto, biasing means tending to move said ejector element out of its normal position, connector means for securing said portion of said fusible element to said conducting element so as to maintain said conducting element in its normal position, said portion of said fusible element normally being in engagement with said ejector element so as normally to hold said ejector element in its normal position relative to said conducting element, and pivotally mounted manual means engageable with said ejector element for moving said ejector element out of its normal position relative to said conducting element thereby physically to break said fusible element, the pivotal mountings for said ejector element and for said manual means being coincidental.

4. An electric fuse comprising a fuse tube, a fusible element disposed within said tube and having one end thereof secured therein and having the other end thereof extending out of one end of said tube, a conducting element secured by pivotal support means to said tube and having a normal position with respect to said tube, an ejector element pivotally supported by said conducting element and having a normal position with respect thereto, connector means for securing said other end of said fusible element to said conducting element thereby to hold said conducting and ejector elements in their normal positions, and manual means interrelated by pivotal mounting means with said conducting element and engageable with said ejector element for moving said ejector element out of its normal position relative to said

conducting element and tube thereby physically to break said fusible element.

5. An electric fuse comprising a fuse tube, a fusible element disposed within said tube and having a portion thereof extending out of one end of said tube, a conducting element secured by pivot means to said tube and having a normal position with respect to said tube, an ejector element secured by pivot means to said conducting element and having a normal position with respect thereto, said portion of said fusible element being interrelated with said conducting and ejector elements so as normally to hold said conducting and ejector elements in their normal positions, a trunnion pivotally connected with said conducting element and constituting a fixed pivot therefore, an offset portion movable with said trunnion and engageable with said ejector element for moving said ejector element relative to said conducting element thereby to break said fusible element, and manually operable crank means movable with said trunnion and offset portion for imparting rotary movement thereto thereby to impart operating movement to said ejector element.

6. An electric fuse comprising a fuse tube, a fusible element disposed in said tube and having a portion thereof extending out of one end of said tube, a movable conducting element having a normal position relative to said tube, a movable ejector element having a normal position relative to said tube, said portion of said fusible element being normally interrelated with said ejector element so as to hold said ejector element in its normal position relative to said tube, a pair of spaced trunnions interrelated with said conducting element by a pivotal connection and interconnected by an offset portion disposed astride said ejector element and engageable therewith, and crank means for rotating said trunnions and offset portion to move said ejector element out of its normal position thereby to break said fusible element.

7. An electric fuse comprising a fuse tube, a fusible element disposed in said tube and having a portion thereof extending out of one end of said tube, a movable ejector element having a normal position relative to said tube, said portion of said fusible element being normally interrelated with said ejector element so as to hold said ejector element in its normal position relative to said tube, a pair of spaced trunnions interrelated with said ejector element by a pivotal connection and interconnected by an offset portion disposed astride said ejector element and engageable therewith, and crank means for rotating said trunnions and offset portion to move said ejector element out of its normal position thereby to break said fusible element.

8. An electric fuse comprising a fuse tube, a fusible element disposed in said tube and having a portion thereof extending out of one end of said tube, a movable conducting element having a normal position relative to said tube, a movable ejector element having a normal position relative to said tube, said portion of said fusible element being normally interrelated with said ejector element so as to hold said ejector element in its normal position relative to said tube, a pair of spaced trunnions interrelated with said conducting and ejector elements by a pivotal connection and interconnected by an offset portion disposed astride said ejector element and engageable therewith, and crank means for rotating said trunnions and offset portion to move said ejector element out of its normal position thereby to break said fusible element.

9. An electric fuse comprising a fuse tube, a fusible element disposed in said tube and having a portion thereof extending out of one end of said tube, a movable con-

ducting element having a normal position relative to said tube, a movable ejector element having a normal position relative to said tube, said portion of said fusible element being normally interrelated with said ejector element so as to hold said ejector element in its normal position relative to said tube, a pair of spaced trunnions interrelated with said conducting element by a pivotal connection and interconnected by an offset portion disposed astride said ejector element and engageable therewith, biasing means tending to move said ejector element out of its normal position against the action of said portion of said fusible element, and crank means for rotating said trunnions and offset portion to move said ejector element out of its normal position thereby to break said fusible element.

10. An electric fuse comprising a fuse tube, a fusible element disposed in said tube and having a portion thereof extending out of one end of said tube, a movable ejector element having a normal position relative to said tube, said portion of said fusible element being normally interrelated with said ejector element so as to hold said ejector element in its normal position relative to said tube, a pair of spaced trunnions interrelated with said ejector element by a pivotal connection and interconnected by an offset portion disposed astride said ejector element and engageable therewith, biasing means tending to move said ejector element out of its normal position against the action of said portion of said fusible element, and crank means for rotating said trunnions and offset portion to move said ejector element out of its normal position thereby to break said fusible element.

11. An electric fuse comprising a fuse tube, a fusible element disposed in said tube and having a portion thereof extending out of one end of said tube, a movable conducting element having a normal position relative to said tube, a movable ejector element having a normal position relative to said tube, said portion of said fusible element being normally interrelated with said ejector element so as to hold said ejector element in its normal position relative to said tube, a pair of spaced trunnions interrelated with said conducting and ejector elements by a pivotal connection and interconnected by an offset portion disposed astride said ejector element and engageable therewith, biasing means tending to move said ejector element out of its normal position against the action of said portion of said fusible element, and crank means for rotating said trunnions and offset portion to move said ejector element out of its normal position thereby to break said fusible element.
